UNITED STATES PATENT OFFICE

JOHN M. BOYD, OF SEATTLE, WASHINGTON

BIT LOCK

Application filed November 19, 1927. Serial No. 234,341.

My present invention relates to improvements in bit locks to prevent loss of the bit at the end of the drilling or boring rod in a drilling machine. As is well known, the 5 drilling bit frequently becomes detached from the drill rod and is lost in the well that is being drilled, causing difficulty, annoyance, and delay in the drilling operations. The object of my invention is to provide an 10 effective means that will retain the bit at the end of the drilling tool and prevent the bit from becoming loosened, thereby preventing loss of the bit.

In carrying out my invention, I provide a 15 locking bolt that is adapted to lock the bit to the drill rod after the former has been screwed to the latter, and means are provided whereby the retaining bolt may with facility be withdrawn in order that the bit 20 may be unscrewed from the rod when desired.

The invention consists in certain novel 25 combinations and arrangements of parts as will hereinafter be more fully pointed out and claimed.

In the accompanying drawings, I have 30 illustrated one complete example of the physical embodiment of my invention wherein the parts are combined and arranged according to the best mode I have so far devised for the practical application of the principles of my invention.

Figure 1 is a view in elevation at the lower 35 end of an earth boring or drilling tool showing the use of the device of my invention;

Fig. 2 is an enlarged detail vertical sectional view at line 2—2 of Fig. 1 showing the bit locked on the lower end of the drill rod;

Fig. 3 is a view similar to Fig. 2 but with 40 the locking bolt withdrawn and the bit released so that it may be unscrewed;

Fig. 4 is an enlarged detail view as at line 44—4 of Fig. 2;

Fig. 5 is a perspective view of the spring 45 pressed locking bolt; and

Fig. 6 is an enlarged perspective view of the lever for the bolt.

In order that the general arrangement and 50 relation of parts may readily be understood, I have shown in Fig. 1 a well known type

of bit as 1 having a shank 2 which is secured to the rod or tool 3. The shank is provided with the usual tapered threaded head 4 and this is screwed into the complementary socket head 5 on the lower end of the tool. 55 The primary object of my invention is to prevent the threaded head 4 from becoming unscrewed from the socket head 5, and to this end I employ a spring pressed bolt 6 located at one side of the longitudinal center of the tool and normally carried in the socket head 5.

The bit shank 2 is fashioned with several 60 sockets indicated as 7 in Fig. 4, and one of these sockets is adapted to receive the bolt 6 as indicated. The bolt is carried in a recess 8 in the socket head 5 and a spring 9 in this recess bears against the spring bolt 6 and tends to force it from its socket 8 into the socket 7 in the bit shank. In locked position 70 as in Fig. 2, the spring retains the bolt in the socket 7 and the bit is thus prevented from turning with relation to the socket head 5.

To withdraw the bolt from its socket 7, I 75 provide a lever 10 which normally lies in a groove 11 in the exterior face of the socket head 5, and this lever coacts with the spring bolt 6 which is provided with a longitudinal slot 12. The spring bolt is equipped with a pin 13 that extends transversely through the bolt and through the slot 12, and the lever 10 is provided with a curved arm 14 of proper width to fit within the slot 12. This curved arm 14 fits around the pin 13 and the shoulders 15 of the lever at the sides of the arm 14 prevent excess movement of the lever. As 80 shown in Fig. 2, the lever 10 lies in the groove 11 and its angular arm 14 engages the pin 13. The angular arm 14 projects through a transverse slot 16 in the socket head and the bent 85 portion of the lever 10 bears against the bottom wall of this slot 16 as the fulcrum when the lever is turned to withdraw the bolt 6. In Fig. 3, it will be seen that the lever 90 has been swung outwardly to withdraw the bolt, in order that the bit may be unscrewed from the socket head. As soon as the lever 10 is released, the spring 9 bearing 95 against the spring bolt quickly moves the 100

bolt and swings the lever 10 into its groove 11 in order to hold the lever in position.

The lever 10 may be turned by slipping the thumb-nail or a sharp edge tool under the 5 free end of the lever to give it the initial movement and then it may be swung by hand to release the spring bolt. After release, the lever 10 is automatically returned to its groove 11 by action of the spring 9.

10 Having thus fully described my invention, what I claim as new and desire to secure by Letters Patent is—

The combination with a bit having a bolt socket and a threaded head, of a complementary 15 interiorly threaded socket head receiving the threaded head, said socket head having an exterior groove and transverse slot, a spring-pressed bolt in said socket head co-operating with the bolt socket and provided 20 with a longitudinal slot, a transverse pin in the bolt-slot, an L-shaped lever having a curved end loosely engaging said pin and adapted to lie in the groove, and lateral stop shoulders on the lever adapted to engage the 25 bolt, whereby said lever co-operates with the bottom wall of the transverse slot to act as a fulcrum when the lever is turned.

In testimony whereof I affix my signature.

JOHN M. BOYD.
